(57) CLAIM

The ornamental design for a cotton candy machine with lazy susan, as shown and described.

DESCRIPTION

FIG. 1 is a top front perspective view of the design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines show portions of the cotton candy machine with lazy susan that form no part of the claimed design.
